A CORPORATION OF OHIO.

COMPOUND BOARD.

1,334,796.

Specification of Letters Patent. Patented Mar. 23, 1920.

Application filed June 16, 1919. Serial No. 304,567.

To all whom it may concern:

Be it known that I, CHARLES G. ROBINSON, residing at 183 Highland avenue, Buffalo, in the county of Erie, State of New York, have invented certain new and useful Improvements in Compound Board; and I do hereby declare the following to be a full, clear, and exact description of the invention, such as will enable others skilled in the art 10 to which it appertains to make and use the same.

The present invention relates to compound board, and has for its object the provision of an improved compound board.

15 Compound or composite board, such as the well known wall board of commerce, is ordinarily made up of two or more sheets or plies of paper stock cemented together with an adhesive, such as silicate of soda. 20 The plies of paper stock, usually about four plies, are suitably fed from rolls into the pasting machine, where the adhesive is applied and the plies forced together by compression, usually by passing the plies with a 25 layer of adhesive between them through compression rolls. The resulting composite board is then usually cut into panels of appropriate size.

30 The paper stock may be made from wood fiber or wood pulp, either ground wood pulp or cooked pulp, used alone or intermixed, or from waste paper or from any other suitable source of fibrous materials. While the composite board may consist of 35 a single layer of material of appropriate thickness, it is ordinarily built up of a plurality of layers or plies of material, as hereinbefore described. Generally, it is marketed in substantially rigid sheets or 40 panels, and is used, generally, as a building material by nailing or tacking it directly to the studding of a room, so that it may serve in place of lath and plaster as the center wall of the room, being usually ornamented with paint, or the like, as desired.

45 Wall board, as manufactured, contains a certain percentage of moisture and also has the characteristic of changing in its moisture content in accordance with the humidity 50 of the surrounding air; these changes ordinarily being slow but nevertheless appreciable. Such changes in moisture content are sometimes very troublesome in new buildings where the moisture initially present in

the lumber, particularly green lumber, 55 gradually works through into the wall board, causing expansion and sometimes warping and buckling. This liability of warping or buckling of the board is the greater and more pronounced, the less rigid 60 is the commercial product. For this reason, it is desirable that the finished board be as rigid as possible, and numerous expedients and instrumentalities have heretofore been practised or suggested in the commercial 65 manufacture of wall board for increasing or improving the rigidity of the product.

The present invention contemplates the provision of a compound board possessed of rigidity in a high degree. At the same 70 time, this increased rigidity is secured without sacrificing any of the other recognized advantageous properties of commercial wall board, such as, for example, its lightness, its convenience of form and dimensions, its 75 relative cheapness, etc. The invention involves the provision of a reinforcing member of reticular form interposed within the body of the compound or composite board. Where the board is made up of a 80 plurality of plies of paper stock, the reinforcing member may form an intermediate ply and in such cases is preferably embedded in the intermediate layer of adhesive 85 adjoining the two plies of paper stock adjacent the reinforcing member. If desired, a plurality of intermediate plies of reticular reinforcing members may be embodied in the composite board. I have found interwoven wire, such as ordinary poultry wire, 90 well adapted as the reinforcing member for the purposes of the invention. In general, the reticular reinforcing member will preferably be of metal, although other materials capable of assuming reticular form 95 and possessing the desired rigidity may, of course, be employed. In some cases expanded metal, and similar reticulated metallic structures, may be used with advantage.

Interwoven wire, such as ordinary poultry 100 wire, is peculiarly advantageous for the purposes of the invention. A single layer or ply of such interwoven wire embodied in the ordinary four-ply wall board of commerce imparts to the product a substantial increase 105 in its rigidity without objectionably increasing its weight or thickness. In the manufacture of the board, the interwoven wire

can be fed into the pasting machine from a roll thereof just as the sheets or plies of paper are fed into the pasting machine. Ordinarily, the reinforcing ply is preferably 5 the central ply of the composite product, and thus in the case of the customary four-ply board, the reinforcing ply of woven wire is embedded in the center of the structure with two plies of paper stock on each side 10 thereof. By the compression to which the plies of paper stock are subjected after being coated with the adhesive, the woven wire is pressed or forced an appreciable distance into the contacting surfaces of the two 15 adjacent plies of paper stock. The interwoven wire is completely covered with adhesive and is confined between two surfaces which are also covered with adhesive, and for this reason may be considered as embedded 20 in the thin layer of adhesive which serves to unite or cement together the two adjacent plies of paper stock.

Paper stock, as it is ordinarily manufactured in the usual paper making machines, 25 is composed of fibers which, generally speaking, extend longitudinally in substantially one direction. This result is brought about by the manner in which the sheets of paper are made in the ordinary paper-making machines. Thus, in the ordinary wood fiber 30 paper stock from which the wall board of commerce is generally manufactured, the fibers extend, for the most part, in one direction, and, on this account, the paper stock is more rigid and tenacious along one 35 axis in its plane than along any other axis. When such wood fiber paper stock is built up into composite board, the relatively weak axes of each ply or sheet of paper extend 40 substantially in the same direction, so that the resulting composite board is less rigid or weaker along one axis of its plane than it is along any other axis. This defect, resulting from the natural tendency of the fibers to 45 arrange themselves in substantially the same direction during the ordinary paper-making process, may very advantageously be overcome by a simple modification of the present invention. Thus, I embody in the structure 50 of the composite board a reinforcing member of reticular form having greater rigidity along a particular axis of its plane than along any other axis, and I arrange this reinforcing member so that its relatively 55 rigid axis is approximately transverse to the relatively weak axis of the plies of paper stock of which the board is composed. This result can be secured by forming the reinforcing member of relatively heavy parallel 60 spaced wires joined by transverse wires of smaller gage or cross section.

In the accompanying drawings, I have 65 illustrated, by way of example, what I now consider to be the best embodiments of the invention. In these drawings,

Figure 1 is a perspective view, partly in section, of a compound board embodying the invention, and

Fig. 2 is a perspective view, partly in section, of a compound board reinforced, in 70 accordance with the principles of the invention, by an intermediate ply of interwoven wire.

Referring to Fig. 1 of the drawings, there is illustrated a compound board made up of 75 four plies or sheets of wood fiber paper stock 5, 6, 7 and 8.

Intermediate the two inner plies of paper stock 6 and 7 is a reinforcing ply 9—10. This reinforcing member is of reticular 80 form, that is to say, it is an open-work structure and more or less resembles a net.

The four sheets or plies of paper stock 5, 6, 7 and 8 have their fibers arranged generally along the axis *a*—*a*. As hereinbefore 85 mentioned, this arrangement of the fibers is the inherent result of the process by which the paper stock is ordinarily made. Because of this arrangement of the fibers, the paper stock, and hence the resulting composite board, can be more easily bent along the axis *a*—*a*, than it can, for example, along the axis *b*—*b*. This inequality in the rigidity of the board along all axes is overcome, in accordance with my present invention, by making the component parts or strands 9 of the reinforcing member of 90 heavier and more rigid material than are the component parts 10 of the reinforcing member. As will be seen by reference to Fig. 1 95 of the drawings, the heavier strands 9, which may be of wire, extend along the axis *b*—*b*, while the relatively weaker and less rigid strands 10, which may be of thin 100 braided wire, extend along the axis *a*—*a*. The braided or twisted strands 10 are suitably secured to the more rigid strands 9 in any appropriate manner.

In Fig. 2 of the drawings, there is represented a reinforcing member 11 in the form 110 of interwoven wire, such as the ordinary poultry wire. This reinforcing member is embedded in the composite board between the center plies 6' and 7' of the four-ply structure 5', 6', 7', 8'.

It will, of course, be understood that the various plies of material in the two modifications of the invention illustrated in Figs. 1 and 2 of the drawings are suitably cemented together by an adhesive, such, for example, as silicate of soda. The reinforcing member of reticular form is entirely embedded and inclosed within the composite structure and is in effect an intermediate ply which is securely cemented to the adjacent 120 plies of paper stock. A very rigid unitary structure is thus obtained, which in external appearance does not differ from the heretofore ordinary commercial types of wall board. However, as the result of the rein- 125

forcing member of reticular form which is embodied in my improved structure, the composite or compound board of the present invention possesses greater rigidity and is better adapted for general use by the trade than are any of the similar forms of composite board now on the market.

I claim:—

1. As a new article of manufacture, a compound board made up of a plurality of plies of fiber stock cemented together, said cemented-together plies of fiber stock being inherently weaker along one axis of their plane than along any other axis, and a reinforcing member associated with said plies of fiber stock for strengthening the board along said inherently weak axis and thereby equalizing the strength of the board in all directions.
2. As a new article of manufacture, a compound board made up of fibrous material with the fibers extending longitudinally in substantially one direction and having a reinforcing member of reticular form of greater rigidity along one axis of its plane than along any other axis thereof, the reinforcing member being arranged with its more rigid axis substantially transverse to

the general direction in which the aforementioned fibers extend.

30

3. As a new article of manufacture, a compound board made up of a plurality of plies of fibrous material cemented together and arranged with the fibers extending generally in one direction, and an intermediate reinforcing ply of reticular form having greater rigidity along a particular axis of its plane than along any other axis thereof, said intermediate reinforcing ply being arranged with its more rigid axis substantially transverse to the general direction in which the aforesaid fibers extend.

35

4. As a new article of manufacture, a compound board made up of a plurality of plies of paper stock cemented together, said board being inherently weaker along one axis of its plane than along any other axis, and a reinforcing member embodied within said board and having greater rigidity along a particular axis of its plane than along any other axis, said reinforcing member being arranged with its relatively more rigid axis transverse to the inherently weak axis of the board.

40

In testimony whereof I affix my signature. 45
CHARLES G. ROBINSON. 50
